UNITED STATES PATENT OFFICE.

HERMANN WEDER, SR., AND CHARLES H. WOLFF, OF PHILADELPHIA, PENNSYLVANIA.

DESIGN FOR A TONGUE-DEPRESSOR.

53,649.

Specification for Design.

Patented July 22, 1919.

Application filed March 20, 1919. Serial No. 283,938. Term of patent 14 years.

To all whom it may concern:

Be it known that we, HERMANN WEDER, Sr., and CHARLES H. WOLFF, citizens of the United States, residing at Philadelphia, in the county of Philadelphia, State of Pennsylvania, have invented a new, original and ornamental Design for a Tongue-Depressor, of which the following is a specification, reference being had to the accompanying drawing, forming part hereof.

Figure 1 is a side view of the tongue depressor; Fig. 2 is a view looking at the rear of the same; Fig. 3 is a view looking at the front of the same; Fig. 4 is a view looking down on the same from the top.

The design is made up of the member C having a flaring apertured end F and member D having a bent end G, and the raised ridge A extending lengthwise of the depressor at the curve B uniting the two parts C and D which extend at an angle to each other and having the ridge where it merges into the part D presenting a flat surface E, all as illustrated.

We claim:

The ornamental design for a tongue depressor, as shown and described.

HERMANN WEDER, SR.
CHARLES H. WOLFF.
